LOCKING DOOR LATCH

Filed Sept. 18, 1950

UNITED STATES PATENT OFFICE

2,686,419

LOCKING DOOR LATCH

Burnie J. Craig, Los Angeles, Calif.

Application September 18, 1950, Serial No. 185,416

5 Claims. (Cl. 70—285)

1

This invention relates to a locking door latch. The general object of the invention is to provide an improved vehicle door latch including novel lock means for controlling the latch on a door of an automotive vehicle.

Another object of the invention is to provide door latching means including a novel lock means which is operable in a novel manner to unlock the latch.

Another object of the invention is to provide a novel door latch handle assembly.

Another object of the invention is to provide a novel coaxial combined key-controlled and dial actuated tumbler controlled lock assembly.

A further object of the invention is to provide a vehicle door latch handle assembly which carries push button means for operating a door latch to release position and wherein a plurality of means is carried by the handle and remote from the push button for rendering the push button member inoperative to open the door.

Other objects and advantages of the invention will be apparent from the following description taken in connection with the drawings, wherein:

Fig. 1 is a central sectional view through a door and pillar, showing the invention;

Fig. 2 is a section taken on line 2—2, Fig. 1;

Fig. 3 is an enlarged section taken on line 3—3, Fig. 1;

Fig. 4 is a fragmentary front elevation showing the handle;

Fig. 5 is a fragmentary section taken on line 5—5, Fig. 3, and

Fig. 6 is a fragmentary section, partly in elevation, showing the locking member.

Referring to the drawing by reference characters, the invention is shown as embodied in a door latch arranged upon the door A of a vehicle which includes a door pillar B.

As shown, each latch includes a base plate 10, having a flange 11 thereon, which is provided with a slot 12 through which a bolt 13 protrudes. The bolt 13 is shown as pivotally mounted on the base plate at 14 and at its outer end supports a strike engaging roller 15.

The latches in the present disclosure are of the type shown in applicant's copending application Serial No. 103,431, filed July 7, 1949, now Patent No. 2,659,230, dated November 17, 1953.

The protruding roller 15 moves in a slot 16 in a strike member 17, arranged upon the car pillar. As fully described in applicant's Patent No. 2,659,230, dated November 17, 1953, the roller moves from one end of the slot 16 towards the other end to fully engaged position, where it holds the

2

door closed due to a catch member 20 pivotally supported at 21 upon the base 10, and which includes notched portions 22 and 23.

The bolt 13 includes a pin 24 which rests upon the notched portion 22 when the bolt is in the disengaged position. When the bolt is moved to safety latched position, the pin engages the notch 23 and when the bolt is raised to fully engaged position (see Fig. 2), the bolt engages a notched portion 25 just above the notch 23. When so engaged the bolt cannot move downwardly to disengaged position until the catch member 20 is swung about its pivot 21 and is released, as will be hereinafter described. A tongue 25' on the base plate limits movement of the catch member in one direction.

One end of a spring 26, arranged about the pivot pin 14, engages a pin 27 on the catch 20 and urges the catch 20 to bolt holding position while the other end of the spring 26 engages a pin 28 on the bolt 13 to normally urge the bolt downwardly to disengaged position.

The bolt may be released by means of an inside remote control door handle (not shown) which is connected by a rod 31 to a rock arm 33 which is mounted on the pivot 21. The lower end of the rock arm engages an actuating pin 34 mounted on a latch releasing member 35. The rock arm will thus move the pin 34 and the pin will move the catch 20, thus permitting the spring 26 to move the latch bolt to disengaged position as the door is opened.

In order to provide means exterior of the vehicle for releasing the catch members 20 and also to provide means for locking the release means against unwarranted operation, a carriage member 36 is provided for each catch. Each carriage member is pivoted on a pivot 37 on the base 10. One end of the carriage member 36 is raised at 36' and a snap-over spring 36'' is arranged between this raised portion 36' and the base 10 to hold the carriage member in either one of its two positions. Tongues 35', struck from the base 10, limit movement of the carriage member 36.

The carriage member 36 includes a projecting end portion 38 which extends through a slot 38' in the flange 11. The end of the portion 38 supports a roller 38''.

The carriage member is similar in some respects in construction and operation to the carriage member shown in Fig. 32 of the applicant's prior Patent No. 2,204,208, granted June 11, 1940.

Guide tongues 39 on the carriage member 36 slidably support the latch release member 35 previously mentioned. When the carriage member

is in the position shown in Fig. 2 and the release member 35 is moved, the pin 34 will engage the tongue 40 on the catch 20 to move the catch. A tongue 41' on the carriage member limits movement of the release member in one direction.

When the carriage member 36 is swung about its pivot 31, the pin 34 will be disposed opposite a slot 40' in the catch 20 so that when the release member 35 moves to releasing position, the pin 34 will move into the slot 40' without moving the catch member 20. The latch just described is fully disclosed and described in the applicant's Patent No. 2,659,230, dated November 17, 1953, mentioned above.

The carriage member 36 includes an elongated slot 46 which is aligned with a slot 47 in the base 10, and the latch releasing member 35 is also provided with a slot 48, aligned with the slots 46 and 47. The slots 46, 47 and 48 receive one end portion of a releasing arm 49, which may be operated from the exterior of the door, as will be described.

The releasing arm is carried by an outside actuator, indicated generally at 50 (see Fig. 1). As shown, the actuator is similar to the handle assembly disclosed in Fig. 2 in the applicant's Patent No. 2,450,372, granted September 28, 1948. As shown the actuator includes a body 51, having a hand grip 52 thereon. A slip plate 52' holds the body 51 in place.

The body 51 includes a bore 53 in which a push member 54 is arranged. The push member 54 includes a flanged portion 55 in an enlarged bore 53' which normally is urged against a shoulder 56 by a spring 57, which also engages a flange 58 on a support 59. A guide washer 60 engages the end of the flange 58 and a split spring 61 holds the parts assembled.

The push member 54 slides in the bore 53 and includes a body having holes 63 therein. In the holes pins 64 carried by the support 59 slide to permit the push member 54 to slide axially relative to the support 59 and to turn therewith. The support 59 is rotatable and includes ears 65 on which the arm 49 previously mentioned and described is pivoted as at 66.

The arm 49 includes a bell crank portion 67 which is engaged by a pin 68 on the lower portion of the barrel of the push member 54 and the construction is such that the arm 49 is rocked by the push member when the latter moves axially. As stated, the arm 49 extends through the slots 46, 47 and 48, the slot 47 being of a size so that its wall is not engaged by the releasing arm 49. The slot 48 is of a size to comfortably receive the releasing arm 49 so that as the push member 54 is pushed inwardly, the arm 49 is rocked, thus moving the latch releasing member 35 to the right in Fig. 1.

This will cause the pin 34 on the latch releasing member 35 to engage the catch member 20, causing the catch member to be rocked, thus releasing the bolt 13 so that the latter may be moved downwardly by the spring 28 as the door opens.

This last described action occurs when the carriage member is in the unlocked—that is, the position shown in Fig. 2. When the carriage member 36 is moved to the locked position and the releasing arm 49 is rocked to shift the latch releasing member 35, the pin 34 will move into a notch 40' in the catch member 20 and thus there will be no releasing action by movement of the latch releasing member 35.

Full movement of the arm 49 by the push member 54 will not move the release member 35 far

enough to move the pin 34 sufficiently to engage the rear wall of the slot 40' so that no unlocking occurs when the carriage member is in unlocking position. However, when the remote control member 31 is pulled it will move the member 33 far enough to shift the pin 34 against the rear wall of the slot 40' to rock the member 20 and release the latch.

From the foregoing description it will be apparent that the latch may be released by operating the push member 54 when the carriage member 36 is in one position and that a similar operation of the pushing member 54, when the carriage member 36 is in the other position, will not serve to open the door. However, the inside release member 31 may be operated to release the catch member and to free the bolt regardless of which position (locked or unlocked) the carriage member may happen to be in.

The body 51 includes another bore 80 from which an enlarged bore 81 extends and from the enlarged bore 81 a further enlarged bore 82 extends. Within the bore 82 a nonrotatable closure 83 is arranged. This closure includes an inwardly directed flange 84 and the closure 83 is held in place by a tight fit and by a split ring 85.

The closure 83 supports a guide sleeve 86 which has tongues 87 thereon passing through slot 88 in the closure. The sleeve includes an internal flange 89 which is engaged by a shoulder 90 on a lock barrel 91. The lock barrel includes a projecting operating portion 92.

A dial member 94 which includes a finger engaging portion 95, has a bore 96 receiving the lock barrel portion 92 previously mentioned. The sleeve 86 is arranged in a bore 97 in the dial member 94. The lock barrel may turn in the sleeve 86 but is normally held against rotation by a pin 100 carried by an arm 101 pivoted at 102 to the closure 83. A spring 103 normally tends to urge the pin 100 into aligned slots 104 and 105 in the sleeve 86 and in one of the arms 105' carried by the barrel 91.

In the lock barrel 91 a core 110 is arranged. This core may be turned by a key 93. The core includes a flange 111 which is engaged by one end of a spring 112, the other end of the spring engaging the closure 83.

The core 110 and the lock barrel 91 are parts of locks of standard construction, the details of which are well known and need not be further described. The construction is such that when the key 93 is inserted in the core 110, suitable pins (not shown) will be aligned, permitting the key to turn the core 110 relative to the barrel 91.

The core 110 carries and turns an operating member 113 which has an offset end 114 fixed thereon.

The offset end 114 of the operating member is disposed in a slot 115 in an extension 115' carried by the carriage member 36, and the construction is such that when the key 93 is inserted the core 110 will be turned, thus turning the operating member 113 and the offset end 114 thereon to move the arm 115' from locking to unlocking position, or vice-versa. The slot 115 is elongated and when the core is in normal intermediate position and the locking member 36 is unlocked, as shown in Fig. 2, the portion 114 will be at one end of the slot. When the carriage member is locked the portion 114 will be at the other end of the slot.

In order to provide for operation of the carriage member 36 to or from locked position without the use of a key, the dial member 95 is ar-

ranged to function with a series of tumblers 120, 121 and 122 which include operating pins 123.

Pins 124, carried by the dial member 94, fit in holes 125 in the tumbler 122 and thus rotate the tumbler when the dial member is rotated. Tumbler locks are in common use and the construction is such that when the dial 94 is properly positioned, tumblers 120, 121 and 122 will be aligned in a desired position. In the present invention each tumbler includes a notch 126 and when the tumblers are properly positioned the notches will be aligned and will be disposed opposite to the arm 101 previously mentioned.

The dial 94 carries a pin 130 which, when the dials are properly positioned, is aligned with a bent portion 131 on the arm 101 so that when the dial is pushed inwardly the pin 130 will engage the arm 101 and rock the arm into the notches 126. This will pull the pin 100 from the slot 105 so that the lock barrel will be declutched from the sleeve 86. When this is done the portion 92 may be rotated to rotate the lock barrel. The lock barrel will turn the core member 110 and the core member will swing the end 114 of the operating member to cause movement of the portion 115 of the carriage member 36.

This last mentioned operation will take place without rotation of the core 110 relative to the lock barrel 91 and, of course, without the use of the key 93.

In the drawings the tumblers 120, 121 and 122 are shown as held spaced apart by annular members 122^a which are held in place by split rings 122^b.

The pins 124 are of such length that when pin 130 has engaged and rocked the arm 101, the pins 124 will not have moved into contact with the tumbler 121.

From the foregoing description it will be apparent that the present invention includes novel means, shown as included in a door handle assembly for opening a door and for controlling the locking and unlocking of the door.

Having thus described my invention, I claim:

1. In a vehicle door lock, a supporting body, a lock barrel movably carried by the body, clutch means holding the lock barrel against movement relative to the body, a head member within the lock barrel, key released means normally preventing relative movement between the head member and the lock barrel, gated tumblers rotatable in the body, a movable fence cooperating with the gated tumblers, a dial member for rotating the tumblers whereby the tumblers may be positioned with respect to one another and to the fence to allow the fence to enter the gatings in the tumblers, said clutch means including a dial moved element associated with the fence in such a manner as to be operable by the dial as the fence is being moved into the gatings to declutch the lock barrel from the body, and operating means on the head member adapted to shift a catch releasing member to a position wherein it may be moved to catch releasing position, the operating means being operable by the head member either when the head member is freed from the lock barrel by the key released means or when the lock barrel is declutched from the supporting body.

2. In a vehicle door lock, a supporting body, a lock barrel rotatably mounted in the body, clutch means normally holding the lock barrel against movement relative to the body, a head member movable in the lock barrel, key released means normally preventing relative movement between

the head member and the lock barrel, gated tumblers rotatable in the body, a movable fence cooperating with the gated tumblers, a dial member for rotating the tumblers whereby the tumblers may be positioned with respect to one another and to the fence to allow the fence to enter the gatings in the tumblers, said clutch means including an element associated with the fence in such a manner as to be operable by the dial as the fence is being moved into the gatings to declutch the lock barrel from the supporting body, a catch releasing member, a movable carriage supporting the catch releasing member, the carriage being shiftable to move the catch releasing member to and from a position wherein it may be moved to and from catch releasing position, and operating means on the head member for shifting the carriage and the catch releasing member to a position wherein the catch releasing member may be moved to catch releasing position, the operating means being operable by the head member either when the head member is freed from the lock barrel by the key released means or when the lock barrel is declutched from the supporting body.

3. In a vehicle door lock, a supporting body, guide means carried by the body, a lock barrel rotatably mounted in the guide means, clutch means normally holding the lock barrel against

movement relative to the guide means, a head member rotatable within the lock barrel, key released means normally preventing relative rotation between the head member and the lock barrel, gated tumblers rotatable in the body, a movable fence cooperating with the gated tumblers, a dial member for rotating the tumblers whereby the tumblers may be positioned with respect to one another and to the fence to allow the fence to enter the gatings in the tumblers, said clutch

means including an element associated with the fence in such a manner as to be operable by the dial as the fence is being moved into the gatings to declutch the lock barrel from the guide means, a catch releasing member, a movable carriage supporting the catch releasing member, the carriage being shiftable to move the catch releasing member to and from a position wherein it may be moved to and from catch releasing position, and operating means in the head member for shifting the carriage and the catch releasing member to a position wherein the catch releasing member may be moved to catch releasing position, the operating means being operable by the head member either when the head member is freed from the lock barrel by the key released means or when the lock barrel is declutched from the guide means.

4. In a vehicle door lock, a chambered body, a fixed sleeve carried by the body, a lock barrel rotatably mounted in the sleeve, clutch means normally holding the lock barrel against movement relative to the sleeve, a head member rotatable within the lock barrel, key released means normally preventing relative rotation between the head member and the lock barrel, gated tumblers rotatable in the chamber, a movable fence cooperating with the gated tumblers, a dial member for rotating the tumblers whereby the tumblers may be positioned with respect to one another and to the fence to allow the fence to enter the gatings in the tumblers, said clutch means including an element engaging the lock barrel and carried by the fence, the fence and element being operated on axial movement of the dial to cause the fence to enter said gat-

5. In a vehicle door lock, a supporting body, a lock barrel rotatably mounted in the body, clutch means normally holding the lock barrel against movement relative to the body, a head member movable in the lock barrel, key released means normally preventing relative movement between

ings and the element to disengage the lock barrel to declutch the lock barrel from the sleeve, a catch releasing member operable to release a catch member, a movable carriage supporting the catch releasing member, the carriage being shiftable to move the catch releasing member to and from a position wherein it may be shifted to catch releasing position, and operating means on the head member for shifting the carriage and the catch releasing member to the position wherein the catch releasing member may be shifted to catch releasing position, the operating means being operable by the head member either when the head member is freed from the lock barrel by the key released means or when the lock barrel is declutched from the sleeve.

5. In a vehicle door lock, a chambered body, a fixed sleeve carried by the body, a lock barrel rotatably mounted in the sleeve, clutch means normally holding the lock barrel against movement relative to the sleeve, a head member rotatable within the lock barrel, an operating member on the head member, key released means normally preventing relative rotation between the head member and the lock barrel, gated tumblers rotatable in the chamber, a movable fence cooperating with the gated tumblers, a dial member for rotating the tumblers whereby the tumblers may be positioned with respect to one another and to the fence to allow the fence to enter the gatings in the tumblers, said clutch means including an element engaging the lock barrel and carried by the fence, the fence and element

being operated on axial movement of the dial to cause the fence to enter the gatings and the element to disengage the lock barrel to declutch the lock barrel from the sleeve, a catch releasing member adapted to be actuated to release a catch member, a movable carriage supporting the catch releasing member, the carriage being shiftable to move the catch releasing member to and from a position wherein it may be shifted to catch releasing position, crank means connecting the operating member to the carriage for shifting the carriage to a position wherein the catch releasing member may be shifted to catch releasing position, and a push button slidably in the chambered body, a latch actuating member on the push button, the latch actuating member being operable by the push button to move the catch releasing member to its catch releasing position when the carriage has been shifted to the position 10 wherein the catch releasing member may be moved to catch releasing position, the crank means being operable by the head member either when the head member is freed from the lock barrel by the key released means or when the lock barrel is declutched from the sleeve.
